AUTOMATIC PIN-SETTER

Ernest Hedenskoog, Muskegon, Mich., assignor to
 The Brunswick-Balke-Collender Company,
 Chicago, Ill., a corporation of Delaware

Application December 14, 1931, Serial No. 580,835

22 Claims. (Cl. 273—43)

This invention relates to an improved automatic pinsetter for bowling alleys and has for one of its principal objects the provision of a machine which will dispense with the services of the pin boy, while at the same time performing, mechanically and automatically, the operations of removing the pins from a bowling alley and resetting the same in position upon the alley for further play.

One of the important objects of this invention is to provide a machine which will remove fallen pins, known as "dead wood" from the alley, while at the same time retaining upright pins upon the alley for additional play.

Another important object of this invention resides in the provision of a device for automatically returning the bowling balls to the player while at the same time resetting the pins, and includes mechanism by which the pins, after falling into or being delivered to the pit are automatically conveyed to the resetting mechanism and distributed there-on in position so that when reset they are in proper position on the alley for play. This operation is accomplished by the player from the playing end of the alley by merely shifting a lever, pulling a chain, pushing a button or the like, there being only two of such operating levers or push-buttons, one for removing dead wood and re-setting part of the pins and the other for sweeping the alley and re-setting all of the pins.

A further object of the invention is the provision, in an automatic pinsetter, of a setting frame for containing a full number of pins to be set in position upon the alley, a storage magazine above the setting frame which empties another full set of pins into the setting frame at the proper time, and means to convey the pins from the bowling alley pit to the storage magazine.

Still another object of this invention resides in the provision of means by which the pins are always presented to the storage magazine with their butt ends foremost, and in proper order, until ten pins are therein, whereupon further delivery is automatically halted.

An object of the invention is the provision of means by which the pins in the storage magazine are automatically delivered to the pinsetter frame whenever the pinsetter frame is empty and when the storage magazine has been filled.

Another object of the invention is to provide improved means for operating the pin-setting, delivering, and handling mechanisms and for properly co-ordinating their movements.

Still another and further object of the present invention is to provide a machine which will set pins upon the bowling alley, return the ball to the

player's position and which includes devices wholly under the control of the player which will remove the dead wood from the alley and reset live pins and which will also clear the alley and position a new set of pins in proper place upon the alley bed, and which furthermore will perform each and all of these operations more quickly and accurately than they can be performed by manual operations.

Another and further important object of the invention resides in the provision of safety devices whereby when the machine has been set by the player to perform a certain operation or while it is performing such operation, it will be impossible for the player to either deliberately or accidentally start the machine upon another operation out of sequence, whereby jamming or faulty handling of the desired movements is avoided.

One object of the invention resides in the provision of improved means for sweeping the pins from the alley whereby the sweep itself moves first in an approximately vertical direction down to the alley bed and then horizontally along the alley bed to clear the same, whereupon it reverses these movements to resume its original position.

Another new feature of the invention resides in a remote control means whereby any pin or pins or combination thereof may be retained in playing position on the alley.

Another object is the provision of means whereby if the operator inadvertently pulls one of the operating cords when the machine is not in position to reset pins or sweep dead wood, the sweep will be tripped allowing it to descend by gravity through a portion of its initial vertical movement when it automatically stops and remains in that position until the machine has completed its cycle or has delivered a full complement of pins to the setter frame whereupon the sweep then automatically resumes its movement, sweeping the bed and returning to its normal position allowing further play.

Another and still further important object of the invention is the provision of a novel means for returning the balls from the pit to the player which means are entirely separate and distinct from the means which deliver the pins from the pit to the magazine and whereby the balls are much more quickly returned, thereby expediting play.

A still further object of the invention resides in the improved elevators for receiving the pins from the conveyor drums which lift them from the pit and which elevators automatically deliver the pins from drums on either side of the pit to

a central chute whence they are directed into the rotary storage magazine.

Other and further important objects of the invention will be apparent from the disclosures in the accompanying drawings and following specification.

The invention, in a preferred form, is illustrated in the drawings and hereinafter more fully described.

Figure 16 is a top plan view of the manually operated control means for the pin selecting device shown in Figures 14 and 15.

Figure 17 is a side view of the control means shown in Figure 16.

Figure 18 is a sectional view of the apparatus shown in Figure 14, taken on the line 18—18 of Figure 14.

Figure 19 is a detail sectional view taken on the line 19—19 of Figure 4 looking in the direction indicated by the arrows.

70 Figure 20 is an elevation of the operating handles and associated control wires, showing the same as adapted to be connected to their associated parts illustrated in Figure 5.

Figure 21 shows the sequence of operations whereby the pin-retaining means of the maga-

zine is moved from pin-dropping to pin-holding position.

Figure 22 is a diagrammatic view showing the electrical connections and associated parts.

Figure 23 is an enlarged detail view of certain portions of Figure 9.

As shown in the drawings—

The reference numeral 10 indicates generally the bed of a bowling alley or the like, having side guards 11 and provided with mechanism supporting frame elements 12 and 13 as best shown in Figure 1. The pins 14 are placed on the alley bed 10 by the improved apparatus of this invention and in the usual progress of the game are knocked down in whole or in part by 15 means of a ball 15.

In the ordinary operation of the game of bowling the pins are collected by a pin boy in the pit of each alley, who places the balls on a track such as that shown at 16 for return to the 20 player and who removes the fallen pins called "dead wood", which may remain on the alley or in the gutters alongside the alley, and who sets the pins as required.

The pin boys usually work with a setter which 25 comprises a triangular frame such as that illustrated at 17 and in the prior practice the boy placed the pins into buckets therein, while the setter is at rest above the alley bed, and then operates suitable mechanism to first depress the 30 setter, deposit the pins on the bed and then elevate the setter out of the way of the pins and balls.

The machine of this invention will automatically perform the operations of delivering the 35 ball from the pit to the return track and setting the pins in the proper position on the alley bed after the bed has been cleared, which operation is also accomplished by the machine at the will of the operator.

The machine will also retain for further play any pins not knocked down by the first ball, while at the same time it will remove fallen pins from the alley, which fallen pins would otherwise interfere with the progress of the game.

40 One of the essential elements of the present invention is the provision of a pair of pin receiving and delivering drums 18 which are continuously rotated while the machine is in operation and which have pockets in the side thereof into which pockets the pins are delivered by gravity from the sloping sides of the pit bed, as shown by the dotted lines in Figure 2. These drums are supported on rotatable spindles 19 and are operated by means of driving chains or the like 50 20, which chains are driven from a main source of power such as a motor or a power shaft 21.

Associated with each of the pin receiving and returning drums 18 is a ball returning element (Figures 11 and 12), each of which comprises essentially an annular rim 22 mounted for free rotation on a corresponding inner rim 23 and driven by means of a belt or the like 24. These ball returning wheels are also continuously operated and when a ball falls against the edge thereof, the edge being preferably covered with rubber or the like, the ball is immediately forced upwardly between the rotating edge and a corresponding pair of rubber covered rails 26. The contact between the balls and the rails forces the balls upwardly and finally delivers them onto a section 65 of the track 16, a section being adjacent to the upper end of each of the ball delivering rims.

In the meantime the pins which have fallen into the recesses in the pin delivering drums 18 75

are carried upwardly and delivered onto a platform 27 (Figures 2 and 12). Pivotaly mounted beneath each platform 27 is a shutter 28 having an extension 29. This shutter 28 normally retains the pin 14 on the platform 27 until a pin elevator, as shown at 30, in its downward motion on supporting rails 31, contacts with the extension 29, depressing the shutter below the level of the platform 27 and allowing the pin 14 to roll over onto the platform of the elevator 30.

Two sets of rails 31 (Figures 7 and 8) are provided, one on each side of a central pin delivering chute 32 into which each elevator alternately delivers pins. Each elevator is driven by means of a chain 33 which runs over a wheel 34, the wheel in turn being mounted on a shaft 35, which shaft has a gear 36 thereon, the gear 36 being in a housing 37 and in mesh with a segmental gear 38 also inside the housing, which segmental gear is moved alternately backward and forward through about one-sixth of a revolution by means of a bell crank arm 39, which is integral with the gear and which arm has pivotally mounted at its lower end an operating connecting rod or the like 40. This connecting rod has its lower end eccentrically mounted on a gear 41 which is in mesh with a pinion 42 on an auxiliary drive shaft 43.

In this manner each of the elevators 30 is alternately raised from its corresponding platform 27 to the top of its supporting rails 31, whereupon any pin resting on the elevator is delivered to the chute 32 by means of the depression of a shutter 44 forming part of the elevator and which normally retains the pin on the sloping floor 30. The shutter is connected by means of a series of levers 45 to a trip arm 46 which contacts with a pin or projection 47 mounted adjacent to the end of the chute 32. When the trip arm 46 strikes the pin 47 the shutter 44 is depressed allowing the pin 14 to drop into the chute 32. (Figure 7).

The chute has a pair of parallel springs 48 mounted along its sides and adjacent the bottom upon which the pins slide, it being found that the pins will slide more freely on springs such as these than on slide rods or the like.

Pin upsetting means in the form of a loop 49 (Figure 1) is pivotally mounted in the bottom of the chute 48 and in the event that a pin is deposited in the chute with its head end first the weight of the head will cause it to fall into the loop 49, whereupon the further action of gravity will cause the pin to tumble over, and thus it will arrive at the bottom of the chute butt end foremost. In the event that the pin is delivered to the top of the chute with its butt end foremost, the upsetting element 49 will have no effect.

Each pin, therefore, will emerge from the end of the chute 32 with its butt end foremost, and is delivered into a respective pin receiving pocket in a rotating magazine 50. This magazine has ten pockets therein, nine of the pockets being spaced around the periphery and the tenth pocket being in the middle. (Figure 3). The tenth pocket, however, has an outside opening facing toward the chute, as shown at 51 in Figures 1 and 3.

As each pin enters the magazine its weight depresses a plate 52 (Figures 3, 9, and 10) mounted on the end of an arm 53. The arm 53 is pivotally mounted at 54, inside a gear housing 55, and has a rearwardly projecting end in the form of a latch, as shown at 56. This latch operates against a corresponding notch in a lever 57 piv-

otally mounted at 58 and having its upper end normally impelled forwardly by a helical spring 59. As soon as the latch 56 is lifted out of the notch in the arm 57, whenever a pin strikes the plate 52, the spring 59 operates the arm 57 to engage the two corresponding members of a clutch 60 mounted on a shaft 61 which leads to the pin magazine 50. The shaft 61 has a beveled gear 62 fixed thereon beneath the magazine 50 and the underface of the magazine is provided with an annular correspondingly beveled gear wheel 63 with which the beveled gear 62 is continuously in mesh. The relation of the beveled gear 62 to the number of teeth in the annular gear wheel 63 is ten to one so that one revolution of the clutch 60 and its associated shaft 61 will rotate the pin magazine 50 through one tenth of a revolution.

This happens at each depression of the plate 52, or, in other words, upon the entry of each individual pin into the magazine. The last of the ten pins enters the magazine through the slide 51 leading to the center pocket and in the meantime the other nine are retained in the pockets by means of the projecting ends 64 of a pin retaining and dropping plate 65 as shown in Figures 9 and 10. After the tenth pin has entered the chute 51 its butt end comes into contact with the lower end 66 of a pivoted stop, the forward end 67 of which stop is then depressed across the face of the chute so that it prevents any more pins from entering the magazine. When this occurs further rotation of the magazine is, of course, stopped until the pins have been delivered from the magazine to the pinsetter. (See Figure 35).

In order to insure that the stop is always open to allow the last pin to enter the magazine, a cam element 68 is projected at the end of a U-shaped frame 69 extending forwardly from the chute, and adapted to ride under this cam element 68 and open the shutter 67 is an operating pin 70 which is fitted in an opening in a support 71.

When the setter frame 17 is empty it will, upon its upward movement and a corresponding motion of its operating shaft 119, operate a trip 72, (Figure 4), which in turn instigates the movement of a single revolution clutch 73 mounted on the side of the gear housing 55 and operated by an auxiliary power shaft inside the gear housing. One revolution of this clutch serves to operate a connecting rod 74 which in turn, through a bell crank lever 75, moves a link 76 rearwardly. This in turn operates a bell crank lever 77, the bell crank lever having at its outer end a trip element 78 which slides behind a cammed latch 79 on a pivoted release bar 80. (Figure 9).

So long as the trip element is behind the release bar the pin holding plate 65 is constrained to move along with the rotating magazine and pins are thereby retained in the pockets of the magazine.

So far as the central or tenth pin is concerned, there is provided a stop element 81 which in Figure 9 is shown in closed position in dotted lines. In the position shown in dotted lines the pin in the magazine is restrained from dropping into the setter frame along with the other nine pins which are in the peripheral pockets of the magazine and held in position by means of the extensions 64 on the plate 65.

A pin 82 is mounted on a pivotally positioned arm 83, which arm supports the stop 81, and be-

neath the pin stop shutter 81 and upon due rotation of the magazine and its associated parts this pin 82 will contact with the nose of the latch element 78, whereupon the pin stop shutter 81 is shifted sideways into the full line position shown in Figure 9 and the tenth pin is dropped into the central pocket in the pin setter frame.

At the moment that the pin is dropped into the setter frame by opening of the shutter 81 it contacts a trigger 91 (Figure 1) in the central bucket of the setter frame, which trigger in turn operates a plunger 92, the end of the plunger impinging against a vane 93 connected by a link 94 to a bell crank lever 95 connected to the extending end of the arm 53 (Figures 1 and 10). This action serves to trip the single revolution clutch 60 previously described which again starts the rotation of the pin magazine.

At the same time movement of the outer end 20 of the arm 83, upon which the stop shutter 81 is mounted, rotatably shifts the plate 65 with relation to the magazine 50, allowing the nine outer pins to drop from the pockets, this pin delivering position being illustrated in Figure 9. The end of 25 the arm 83 is bifurcated to make proper connection with a bolt or rivet on the plate 64.

After the pins have been dropped, a cam 84 mounted in the under-face of the magazine housing rides under the end of the pivoted release bar 80 allowing the nose 78 of the bell crank lever 77 to be released from the latch 79. In order that the parts may resume a normal position whereby the pins are again supported in the rotating magazine, a lug 85 is mounted on the 30 under-face of the plate 65 and adapted to contact with this lug is a retarding element 86, pivotally mounted at 87 on the frame of the machine. When the lug 85 contacts with the retarding element 86, the plate 65 is restrained 35 from moving with the magazine until a cam 88 on the outer face of the gear wheel of the magazine housing rides under the pivoted end 89 of the retarder 86 allowing it to move away from the outer surface of the gear housing sufficiently to 40 permit passage of the lug 85 through a slot 90 in the retarder element 86. When this occurs the plate 65 again moves in unison with the magazine housing 50 and any pins dropping into the magazine are retained therein.

50 On account of the fact that the arc of movement restrained by the retarder 86 is just one twentieth of the periphery of the plate 65, each end 64 is moved just that far, as shown by the dotted lines in Figure 9.

55 After the pins have been deposited in the setter frame and it is desired to position them upon the alley for play, the operator pulls a cord, operates a button or the like at his end of the alley (Figure 20); this in turn operates a cable or cord 96, this being connected at its lower end to a lever 97 fixed on a shaft 98, which shaft is positioned in the gear housing 55 (Figure 4). Rotation of this shaft engages a clutch 99 which is mounted on a shaft 100 which shaft has on its outer end an arm 101 to the end of which is pivotally connected an eccentrically operating arm 102 (Figure 3), the forward end of which arm is pivotally connected to the upper end of a sweeper operating arm 103, this being pivotally mounted at 104.

Parallel to this arm 103 is an arm 105 (Figure 1) mounted at 106 to the frame of the machine and having its lower end pivotally connected by a bell crank lever 110 to a link 107, the outer end

of which is pivotally connected to a sweeper plate or the like 108. Also pivotally mounted on the sweeper plate is link 109 which is parallel to the link 107, the inner end of which last named link is pivotally connected to the center of the bell crank 110 at the pivotal point of juncture between it and the lower end of the arm 103.

5 A supporting link rod, or wire, in a form of a strain relief element is shown at 111, the lower end being connected to the top of the sweeper plate 108 and the upper end being mounted adjacent the pivotal point of connection of the arm 103 with the frame. The clutch which operates the sweeper shaft 100 is a single revolution clutch and therefore one rotation of the shaft will move 15 the sweeper downwardly to the alley, rearwardly along the alley to sweep all pins off the same, thence forwardly along the alley and upwardly to its original position.

At the same time that the clutch 99 is being 20 engaged a clutch 112 on the shaft 98 is also engaged (Figure 4), this clutch in turn normally making a single revolution and rotating an eccentric plate 113 (Figure 5) which has mounted on its periphery an annular eccentric connecting 25 rod 114, this in turn being connected at its lower end by a link 115 to a plate 115 which has a slot 116 therein. This plate extends upwardly and parallel to the eccentric connecting rod. In the lower end of the slot is mounted the end of a link 30 117 which is connected at its forward end to an extension 118 on the shaft 119 which operates the setter frame, by which the pins are deposited on the alley.

When the lower end of the connecting rod 117 35 is in the bottom of the slot 116 a fairly limited movement is imparted to the shaft 119 for the setter frame, and as a consequence the arms 120 extending forwardly from this shaft will move the setter frame downwardly through only a portion 40 of its travel.

By referring to Figures 4 and 5 it will be noted that gear 42, helical gear 170, bevel gear 176, and worm gear 177 are all mounted on the central shaft 61 which is constantly driven by the worm 45 178 connected directly to the motor. The gear 170 drives the cross-shaft which has the gears 172 and 174 thereon, and upon this shaft is also positioned the clutch 13 which is mounted outside the housing 55. The driving connection between 50 the gear 170 and the aforesaid shaft is accomplished by means of the gear 171. The gear 172 meshes with the gear 173 and drives the cross-shaft which operates the setting frame by means of the eccentric 113.

55 The gear 174 is in mesh with the gear 175, which last named gear is mounted on the shaft 100. This shaft operates the sweeper.

In order to obtain a new set of pins, the operator or player pulls the wire 96 whereupon the clutch 99 is engaged and this actuates the sweeper apparatus, shaft 100, which shaft has a cam 179 thereon (Figure 5) and at a certain point in the rotation of this cam the lever 180 is raised, as illustrated, which lever includes an extension. 65 The extension in turn engages the pin 181 on the connecting link 117 whereupon this connecting link 117 is raised to topmost position so that the pin at its further end will fit into the notch 182 at the top of the slot 116. After this has been 70 accomplished the clutch 112 is engaged by operation of the cam 183, lever 184, and shaft 98 (Figure 4). The shaft 98 has a shifter yoke 185 thereon which engages the clutch 112 whereupon 75

rotation of the shaft on which the arm 115 is positioned takes place and the arm 115 is pushed forward and through the link 117. The arm 118 on the shaft 119 is moved forwardly to the maximum extent of its movement and the pin setter arm 120 with the pin setter frame thereon is accordingly depressed to its lowermost position, as shown in the dot and dash lines in Figure 5. This lowermost position of the spotting frame is at the alley bed and allows of the positioning of a new set of pins upon the bed.

In order to remove dead wood or fallen pins from the alley while certain of the standing pins are still in play, the operator pulls the wire 127 which immediately engages the clutch 112 whereupon the arm 115 is similarly actuated, with, however, the end of the link 117 in its lowermost position, shown by the full lines in Figure 5, whereupon the arm 120 which supports the setter frame will be shifted to its middle position, shown in the dotted lines in Figure 5, which middle position brings the setting frame down to the top of the pins and accordingly raises the standing pins from the alley bed on its return stroke.

When the setter frame is moved only slightly downwardly, as explained above, it will not contact with the alley and no pins will be deposited on the alley. However, mounted on the setter frame, as shown in Figure 1, are ten magnets, preferably electro-magnets, 121, and in the head of each pin is a soft iron plug. The setter frame is moved sufficiently downwardly by the action of the link 117 in the lower end of the slot 116 so that it will contact with the tops of any pins standing on the alley. The action of the magnets, which are automatically excited by this movement through a contact switch 122 and corresponding connections 123 (Figure 5), will then lift the pins from the alley; when the setter frame is again moved up upon the completion of the rotation of the eccentric plate 113. This is done before the sweeper arm 108 sweeps the alley, so that any pins left standing on the alley are removed out of the way of the sweeper arm and the sweeper arm is allowed to clean the alley of fallen pins known as "dead wood". The standing pins are then re-deposited on the alley for further play.

Whenever it is desired to position an entirely new set of pins upon the alley, as, for example, when all the pins have been knocked down or at the beginning of a play, the operator pulls the handle 126 connected to a corresponding wire or cord 127 (Figures 5 and 20) and this in turn operates a release lever 128 (Figures 4 and 13). This release lever is positioned on the end of the shaft 129, the main portion of which is in the gear housing 55. A rotation of this shaft 129 operates the clutches 99 and 112 the same as the corresponding rotation of the shaft 98, but in the case of the shaft 129 an additional operation is accomplished in that the link 117 is raised so that the pin at its rear end will be in the upper portion of the slot 116 of the plate 115, whereby a movement of this plate will impart a correspondingly greater movement to the link 117, the bell-crank lever 118, and associated parts, including the setter frame supporting links 120, whereby the setter frame links will be moved to the lowermost position, as shown in the dotted lines in Figure 5, these in turn dropping the setter frame to the alley bed and depositing a full set of pins thereon. The exact action of the setter frame in depositing the pins upon the alley bed upon contact therewith is old in the art and will not be here described in

any detail. Before this depositing of the pins occurs, however, the sweeper is operated in the usual manner to clear the alley of any fallen or other pins which might have been thereon.

The block between the lower ends of the arms 128 is for the purpose of locking them against accidental operation when the machine is passing through one or the other sequences of movement as hereinbefore described. Therefore, if a player in the excitement of the game pulls the handle 126 after he has rolled the first ball along the alley, and has failed to knock down all the pins, and it becomes necessary to replace the pins not knocked down by the first ball, this is readily accomplished without requiring an attendant to manually place the pins upon the alley bed, by simply locking the magnetic control for the setter frame at the player's end of the alley, whereby any desired pin or pins may be removed without disturbing the position of the others. This, besides enabling the correction of errors as aforesaid, when the player pulls the new-set handle instead of the handle for the removal of dead wood, also permits the player to practice by bowling against certain combinations of pins or against any special pin in a certain position. This is best shown in Figures 14 to 17 inclusive and comprises essentially a plurality of electrical contact arms 124, as best shown in Figure 14, there being ten of these, one for each pin-controlling magnet, these arms being adapted for individual energization of the magnets 121 of the setter frame. The means for operating this device is preferably positioned on the newel post of the ball-return rail adjacent the player's end of the alley, as best shown in Figures 16 and 17. An operating handle 140 is mounted on a plate at the top of the newel post, adapted to be rotated in a circular band 141, this band having ten notches therein corresponding to the number of pins. The handle is pivoted on the plate as at 142 and can be moved into an upward position, as best shown in dotted lines in Figure 17, for rotation around the band. To the inner end of the handle is attached an operating cord or cable, 145, and this passes through a sleeve 143 which is fastened to the handle plate which sleeve extends downwardly through the newel post, terminating in a sheave or the like 144. A cable 146 leads from this sheave and extends beneath the floor of the alley to the apparatus illustrated in Figure 14, which is mounted on a convenient portion of the mechanism below the shaft 119, which shaft operates the setter frame.

The cable 146 is attached to an operating rod 134 which extends longitudinally through the device for controlling the magnets, as best shown in Figure 14, and a pull on the cable 146, on account of a corresponding rotation of the handle 140, moves the rod 134 through the magnet setting mechanism for a distance corresponding to the arc through which the handle 140 has been moved. The pull on the cable is counteracted by means of a helical spring 147 mounted on the outer end of the rod and adjustably maintained in position thereon by means of a nut or the like 148. The magnet control setting lever is mounted on the rod 134, which rod is square in cross-section and slidably mounted in suitable bearings 149 which are rotatably positioned in plates 150 forming supporting ends or a housing for this magnet control mechanism.

Mounted on the rod 134 and adapted to slide therewith within the confines of the plates 150 is a switch setting lever 133. The end of this

lever is adapted to move over the upper ends of a row of switch operating pins 168, of which there are ten, corresponding in number to the number of bowling pins. The cord or cable 145, which is tightened by depression of the handle 140 on the newel post, is connected at its farther end to the outer end of a link 151 (Figures 14 and 15), the inner end of which is mounted on the rod 134, as best shown in Figure 15, and upward movement of the cable 145 will result in the rotation of the rod 134 around its axis and a corresponding depression of the extension 133 thereon.

Accordingly a turning movement of the handle 140 through a portion of its arc of motion, and its depression into one or more of the slots in the circular plate 141, will result, first, in a corresponding longitudinal movement of the rod 134 with respect to the plates 150 and the switch elements therebetween, and second, a depression of the handle into the same, causing corresponding depression of the latch element 133 against the particular push-rod over which it happens to be at that particular point in its slidable movement; this in turn depresses one of the leaf springs or contacts 124 mounted in the housing 150, which thereupon makes an electrical contact between the inner ends of the binding posts 152 and 153.

30 A series of springs 137 is provided in the rear of the housing 150. Each of these springs operates against a push-rod 136, which, when any one of the pins 168 is depressed by action of the lever 133, rides under the enlarged head of the pins 168 and retains the same in depressed position. All of the pins 168 and 136 are slidably mounted in a suitable retaining element 167 (Figure 18).

In addition to the element 133 which individually depresses the pins 128, a plate 159 extends longitudinally over all the pins in such a position as to simultaneously contact all their heads while at the same time allowing of a contact therewith of the latch member 133, and this plate is fastened upon or forms part of a rod or shaft which is fitted into suitable bearings in the endplates 150 and has mounted at its outer end an operating bell-crank lever 160. The outer end of this lever is connected by means of a connecting-rod 131 to the outer end of an arm 132 mounted on the shaft 119, which shaft operates the pin setter frame.

An upward movement of the link 131 causes a corresponding depression of the plate 159, whereby all of the pins 168 are forced into current closing position, as shown in Figure 18, and consequently all of the magnets in the setter frame are excited into pin-lifting position. This action is necessary when the setter frame moves downwardly to remove dead wood from the alley as hereinbefore described, while at the same time retaining upright pins upon the alley for further play.

In Figure 15 the spotting frame shaft is shown in its lowermost position, whereby all the magnetic contacts are locked.

It will be evident from an inspection of Figure 15 that operation of the individual pin setting and retaining elements through the cord or cable 145, while at the same time rotating the shaft or rod 134 around its axis, depresses a link 154 connected thereto by means of an eccentric arm 155 and forces a latch 156 into locking position with a corresponding notch in the end of the bell-crank lever 160. When, however, the rod 131

is again moved upwardly by operation of the setter frame, the shaft upon which the plate 159 is mounted is rotated, and integral with this plate 159 is a right-angle extension 157 the end of which fits under corresponding extensions on the push-rods 136 whereby an upward pull on the rod 131 results in an outward movement of the push-rods 136, allowing the leaf spring switches 124 to return the pins 128 to normal open circuit position.

The current for the magnets is preferably from a battery 136 (Figure 22) or other source of direct current, which can be supplied as desired or convenient.

A switch 137 is provided for making the initial current connection, this being operated by a cam 138, this cam being initially rotated or started by means of a lever 122 (Figure 5) when the machine is used for dead wood only, whereupon this switch is engaged.

It is possible, by energizing certain magnets by means of the push-rods, to produce corresponding pin-lifting effects when the pin setter frame reaches the bottom of its shorter travel in the dead wood operation, the other magnets 25 being unenergized or dead. Upward movement of the frame will then carry with it the pins corresponding to the energized magnets, and the sweeper arms the remainder. If, therefore, the new-set handle has been pulled when the dead 30 wood operations should have been performed, the desired pins, only, may be positioned upon the alley by a shifting of the handle 140 into the slots corresponding thereto and a pulling of the dead wood operating cord or handle.

It is possible with the arrangement just described to leave desired individual circuits ready for completion during the dead wood operation, so that repeated shots may be made at the same combination of standing pins in practice, it being only necessary that after each ball has been rolled along the alley bed a new set of pins be deposited and the dead wood button subsequently pressed to remove those not desired.

The operation of the machine presupposes the use of from twenty to twenty-three pins, ten being either on the alley, in the pit, or in the elevators. The cam 58 opens the setter and the tenth pin closes the setter, thereby allowing as many as three extra pins to remain in the chute, 50 as shown in Figures 1 and 21, making a total of twenty-three pins.

The motor is started to furnish the necessary power and the machine is then ready for operation. The player takes his position at the player's end of the alley and if no pins are upon the alley bed he pulls the new-set handle 126, which, through the mechanism previously described, causes the sweeper blade 108 to descend and sweep the alley bed to insure that it is clear 60 of pins and balls. The pin setter 17 then descends and deposits a set of pins upon the spots in the alley bed and returns to normal upward position. The player then rolls a ball along the alley bed, knocking down all or some of the pins. 65

If he knocks down all of the pins, this is known as a "strike" and affords a certain scoring total. If, on the other hand, only some of the pins are knocked down, this is known as a "split" and the player then has the privilege of rolling another ball at the pins left standing. However it is of course necessary to first clear the alley of any fallen pins which might accidentally remain thereon. To accomplish this the player pulls the lever or handle attached to the cable 75

96, and this, through the mechanism previously described, causes the pin setter to descend until the magnets 121 are just clear of the heads of any standing pins. These magnets are simultaneously energized through the action of the switch lever 122 and as the pin setter again ascends the standing pins are lifted from the alley bed. The sweeper blade then operates to sweep the dead wood into the pit and as it returns to normal position the setter frame again descends to replace the lifted pins in position upon the alley bed from which they were lifted, after which it returns to normal elevated position. The player may then continue the play.

15 Meanwhile the drums 18 and the elevators 30 and 31 carry the pins from the pit to the chute 33, whence they are delivered to the rotating magazine 50, the magazine having previously been emptied to deliver another set of pins into the setter frame, this having been accomplished upon the next upward movement of the setter frame after the original depositing of a full set of pins upon the alley bed.

20 At the same time any balls in the pit are delivered upwardly, by means of the ball-return elements 22 to 26, inclusive, to the ball return rails 16, whence they roll by gravity back to the player's end of the alley.

25 I am aware that many changes may be made and numerous details in construction varied throughout a wide range without departing from the principles of this invention, and I therefore do not purpose limiting the patent granted hereon otherwise than as necessitated by the prior art.

30 I claim as my invention—

1. An automatic bowling pin setter, including means for depositing a set of pins on an alley, removing fallen pins and replacing any upright pins, and a conveyor for delivering fallen pins in horizontal position from the pit to the setting mechanism, said conveyor including a pair of alternately operating reciprocating elevator platforms, together with means at the players' end of the alley for selectively instigating the operation of the pin setting or removing means.

2. In an automatic pin setter, the combination of a setting frame, a combined ball and pin return comprising a continuously rotated wheel, a rim on the wheel for contact of balls and recesses in the wheel for reception of pins and a set of stationary rails associated therewith, and means controlled by the player for removing fallen pins from the alley and resetting live pins.

3. In an automatic pin setter, the combination of a setting frame, a ball return comprising a continuously rotated wheel and a set of stationary rails associated therewith, means controlled by the player for removing fallen pins from the alley and resetting live pins, and additional means including bell crank levers for clearing the alley and positioning a new set of pins upon the bed, together with safety means for preventing the accidental initiation of one operation while another operation is taking place, said safety means including a block between the ends of the bell crank levers.

4. In an automatic bowling pin setter, the combination of improved means for sweeping the pins from the alley, means for operating the same, comprising a shaft and lever connection for moving the sweep first in an approximately vertical direction downwardly and thence horizontally along the alley bed to clear the same, and additional elements for reversing these

movements to cause the sweep to resume its original position, together with an automatic safety means for halting the operation of the sweep if motion thereof has been instigated out of proper sequence, said means including a retractable block.

5. In an automatic pin setter for bowling alleys, means for setting the pins on the alley, means for sweeping the fallen pins off the alley, means for retaining any upright pins in position for further play, separate operating means at the players' end of the alley for separately initiating the pin setter movement and the dead wood sweeping-and-resetting movement, an automatic block for preventing the initiation of one operation while another is incompletely, and means for optically warning the player and blocking the alley in the event that one of the operating mechanisms is initiated while the machine is performing the other cycle of operations.

6. Bowling mechanism, including pin assembling means for intermittently collecting the pins in a circular formation having a center pin in alignment with the axis of the triangularly related pin positions, setting means for receiving the pins in triangular formation from the circular formation, and means for delivering the pins from the setting means to playing position.

7. Automatic pin setting mechanism for bowling alleys, including a setter frame, pin assembling means therefor, a ball collector and conveyor means for returning the balls to playing position, and a common operating means for the ball collector and pin assembling means, the ball collecting means including a constantly rotated circular frame, a fixed semi-circular frame adjacent the rotatable frame and concentric therewith, and friction means on the edges of the frames for gripping balls and rolling same between the frames.

8. Automatic pin setting mechanism for bowling alleys, including a setter frame, pin assembling means therefor, a ball collector and conveyor means for returning the balls to playing position, and a common operating means for the ball collector and pin assembling means, the ball collecting means including a constantly rotated circular frame, a fixed semi-circular frame adjacent the rotatable frame and concentric therewith, and friction means on the edges of the frames for gripping balls and rolling same between the frames, and delivery rails associated with said frames.

9. Automatic pin setting mechanism for bowling alleys, including a setter frame, pin assembling means therefor, a ball collector and conveyor means for returning the balls to playing position, and a common operating means for the ball collector and pin assembling means, the ball collecting means including a constantly rotated circular frame, a fixed semi-circular frame adjacent the rotatable frame and concentric therewith, and friction means on the edges of the frames for gripping balls and rolling same between the frames, and delivery rails associated with said frames, said delivery rails leading to the players' end of the alley.

10. In a pin setting machine for bowling alleys, the combination of a pin setter adapted to deposit a set of pins on an alley bed, and means for operating the same, said means comprising a rotatable shaft and arms connecting the shaft to the pin setter, and means for selectively rotating the

shaft through a complete and a partial setter frame movement.

11. In a pin setting machine for bowling alleys, the combination of a pin setter adapted to deposit a set of pins on an alley bed, and means for operating the same, said means comprising a rotatable shaft and arms connecting the shaft to the pin setter, and means for selectively rotating the shaft through a complete and a partial setter frame movement, said means comprising an operating arm on the shaft, a link connected to the operating arm, reciprocable means for shifting the link approximately longitudinally, and means for regulating the effective motion of the link.

12. In a pin setting machine for bowling alleys, the combination of a pin setter adapted to deposit a set of pins on an alley bed, means for operating the same, said means comprising a rotatable shaft, arms connecting the shaft to the pin setter, means for selectively rotating the shaft through a complete and a partial setter frame movement, said means comprising an operating arm on the shaft, a link connected to the operating arm reciprocable means for shifting the link approximately longitudinally, and means for regulating the effective motion of the link, said means comprising a plate having a slot therein and a pin on the end of the link movable from top to bottom of the slot.

13. In a pin setting machine for bowling alleys, the combination of a pin setter adapted to deposit a set of pins on an alley bed, means for operating the same, said means comprising a rotatable shaft, arms connecting the shaft to the pin setter, means for selectively rotating the shaft through a complete and a partial setter frame movement, said means comprising an operating arm on the shaft, a link connected to the operating arm, reciprocable means for shifting the link approximately longitudinally, means for regulating the effective motion of the link, said means comprising a plate having a slot therein and a pin on the end of the link movable from top to bottom of the slot, and driving means for shifting the plate to operate the link.

14. In a pin setting machine for bowling alleys, the combination of a sweeper for removing fallen pins from the alley, and means for operating the same, said means comprising a frame and means connected to the frame for moving the same downwardly and then returning the same to normal raised position, said frame including links for maintaining the sweeper blade in a vertical position throughout said movement.

15. In an automatic pin setter for bowling alleys, a rotatable storage magazine, a chute for delivering pins singly into the magazine, trip means for moving the magazine through one-tenth of its revolution upon the entry of each pin thereinto, further trip means for stopping the rotation of the magazine when it is full, a pin setter frame below the magazine, a trip element in the setter frame connected to the magazine whereby a full set of pins is delivered from the magazine to the setter frame when the setter frame is empty and if the magazine is full, and means for automatically withholding operation of the setter frame until the full complement of pins has been delivered from the magazine to the frame.

16. In a pin setting machine for bowling alleys, the combination of means for depositing a desired and variable number of pins on the alley bed in desired and variable arrangement and means for

clearing the alley prior to the positioning of said pins, said first-named means including a set of electromagnets and means operated from the players' end of the alley for individually controlling the magnets, said means comprising a dial, a plurality of notches in the dial corresponding to the number of pins, and a handle adapted to be shifted into the notches for designating those pins to be retained on the bed.

17. In a pin setting machine for bowling alleys, the combination of means for depositing a desired and variable number of pins on the alley bed in desired and variable arrangement and means for clearing the alley prior to the positioning of said pins, said first-named means including a set of electromagnets and means operated from the players' end of the alley for individually controlling the magnets, said means comprising a dial, a plurality of notches in the dial corresponding to the number of pins, a handle adapted to be shifted into the notches for designating those pins to be retained on the bed, and means for rotating the dial with the handle when positioned in the notches.

18. In a pin setting machine for bowling alleys, the combination of means for depositing a desired and variable number of pins on the alley bed in desired and variable arrangement and means for clearing the alley prior to the positioning of said pins, said first-named means including a set of electromagnets and means operated from the players' end of the alley for individually controlling the magnets, said means comprising a dial, a plurality of notches in the dial corresponding to the number of pins, a handle adapted to be shifted into the notches for designating those pins to be retained on the bed, means for rotating the dial with the handle when positioned in the notches, a series of electric switches connected to the electromagnets, and mechanical means leading from the dial and handle to the switches for operating the same.

19. In a pin setting machine for bowling alleys, the combination of means for depositing a desired and variable number of pins on the alley bed in desired and variable arrangement and means for clearing the alley prior to the positioning of said pins, said first-named means including a set of electromagnets and means operated from the players' end of the alley for individually controlling the magnets, said means comprising a dial, a plurality of notches in the dial corresponding to the number of pins, a handle adapted to be shifted into the notches for designating those pins to be retained on the bed, means for rotating the dial with the handle when positioned in the notches, a series of electric switches connected to the electromagnets, mechanical means leading from the dial and handle to the switches for operating the same, and means adjacent the switches and operated by said mechanical means for selectively making and breaking the electrical contact of the switches.

20. In a pin setting machine for bowling alleys, the combination of means for depositing a desired and variable number of pins on the alley bed in desired and variable arrangement and means for clearing the alley prior to the positioning of said pins, said first-named means including a set of electromagnets and means operated from the players' end of the alley for individually controlling the magnets, said means comprising a dial, a plurality of notches in the dial corresponding to the number of pins, a

handle adapted to be shifted into the notches for designating those pins to be retained on the bed, means for rotating the dial with the handle when positioned in the notches, a series of electric switches connected to the electromagnets, 5 mechanical means leading from the dial and handle to the switches for operating the same, means adjacent the switches and operated by said mechanical means for selectively making and breaking the electrical contact of the switches, and additional means for simultaneously connecting all the switches.

21. In a pin setting machine for bowling alleys, the combination of means for depositing a desired and variable number of pins on the alley bed in desired and variable arrangement and means for clearing the alley prior to the positioning of said pins, said first-named means including a set of electromagnets and means 15 operated from the players' end of the alley for individually controlling the magnets, said means comprising a dial, a plurality of notches in the dial corresponding to the number of pins, a

handle adapted to be shifted into the notches for designating those pins to be retained on the bed, means for rotating the dial with the handle when positioned in the notches, a series of electric switches connected to the electromagnets, 5 mechanical means leading from the dial and handle to the switches for operating the same, means adjacent the switches and operated by said mechanical means for selectively making and breaking the electrical contact of the switches, and 10 additional means for simultaneously connecting all the switches, together with further means for simultaneously releasing all the switches.

22. In an automatic pin-setter for bowling alleys, means for elevating the pins from the 15 bowling alley pit to a point above the alley, said means including an elevator platform; and means for maintaining the platform in a horizontal pin-supporting position on its upward and downward travel and for tilting the platform into an approximately vertical pin-delivering position at the upper end of its travel.

ERNEST HEDENSKOOG.
